UNITED STATES PATENT OFFICE

GEORGE H. WHITTINGHAM, OF BALTIMORE, MARYLAND; SAFE DEPOSIT AND TRUST COMPANY OF BALTIMORE AND ELEANOR V. D. WHITTINGHAM, EXECUTORS OF SAID GEORGE H. WHITTINGHAM, DECEASED, ASSIGNEES TO MONITOR CONTROLLER COMPANY, OF BALTIMORE, MARYLAND, A CORPORATION OF MARYLAND

MOTOR CONTROL SWITCH MECHANISM

Application filed April 22, 1931. Serial No. 532,065.

This invention relates to improvements in switches for controlling electric motors. Machine tools in factories are commonly equipped with individual driving motors, and, at a point convenient to the operator of the machine, push button switches are arranged for controlling an electro-magnetic switch or contactor which operates to start and stop the motor. It is found desirable to provide manually operable means for opening the motor circuits, to stop the motor, in case of failure of the electromagnetic switch to open when the stop push button is pressed. Such failure may arise, for instance, through such grounding of the magnet coil as would short-circuit the push button switches and leave the coil energized.

In the present invention, I have associated with the electromagnetic switch a block of insulating material carrying the normally stationary contacts of the switch, and means whereby this block may be quickly moved, by the operation of a hand lever, to carry these contacts away from the movable arm of the switch, thereby opening the motor circuit and also disconnecting the magnet coil from the supply circuit. In this movement of the contact-carrying block, the circuit to the motor is broken at a plurality of points, thereby minimizing the arcing at the contacts. After the fault in the electromagnetic switch has been repaired, the contact-carrying block may be returned to its normal position by a reverse movement of the hand lever.

In the accompanying drawings,

Fig. 1 is a front elevation of a three-pole switch mechanism;

Fig. 2 is a side elevation of the same, looking from right to left in Fig. 1;

Fig. 3 is a central vertical section through the switch mechanism;

Fig. 4 is a cross section on the line 4—4 of Fig. 3;

Fig. 5 is a diagrammatic view showing the circuits, the switch mechanism being shown in front elevation, with parts removed;

Fig. 6 is a front elevation of a single pole switch with a blow-out magnet;

Fig. 7 is a central vertical section through the same;

Fig. 8 is a transverse section on the line 8—8 of Fig. 7, and,

Fig. 9 is a detail view of one of the pole pieces of the blow-out magnet.

Referring to Figs. 1 to 5 inclusive of the drawing, *a* indicates a suitable base, of insulating material, upon which is mounted an electromagnet *b* to which is hingedly connected an armature 1. A strip of insulating material 2 is secured to the armature, and contact fingers 3, 4, and 5 are yieldingly mounted upon the strip. These contact fingers carry metal parts 3^a, 4^a, and 5^a at their free ends, each adapted to engage a pair of normally stationary contacts, when the armature is attracted by the magnet.

These pairs of contacts, 6—7, 8—9, 10—11, which may be termed main switch contacts, and other contacts 12, 13, and 14, which may be termed line contacts, are mounted on a block of insulating material *c* which is arranged between and secured to two metal bars, 15 and 16, the lower ends of which are hinged to posts 17 and 18, respectively, and these posts are secured to the base *a*. The bars 15 and 16 and the block with its contacts are normally supported in the position shown in full lines in Fig. 3 by a toggle mechanism, but they will be moved quickly by springs *s* into the dotted line position, Fig. 3, when the toggle mechanism is tripped. The toggle mechanism will be hereinafter described.

The block *c* has upstanding side walls 19, longitudinal partitions 20 and a transverse partition 21. These walls and partitions constitute arc-shields. The partition 21 forms a shield between the contacts 12, 13 and 14 and the adjacent contacts 6, 8, and 10 and the longitudinal walls and partitions constitute shields between these pairs of contacts 6—7, 8—9, 10—11, and between the several contacts 12, 13, and 14.

Three similar metal strips 22 are secured to a block of insulating material 23 on the base and these metal strips have downwardly turned ends which carry binding posts 24, 25, and 26 to which the terminals of the supply circuit are connected. As illustrated in Fig. 3, the support 22 has an overturned end

22^a and the binding post 25 is secured to this overturned end. Contact strips 27, 28, and 29 extend from the binding posts 24, 25, and 26 to the contacts 12, 13, and 14, respectively. 5 The strips have enlarged openings through which the binding posts extend and on each binding post is a spring 30 which presses the strip toward the flanged end of its support 22. When the block *c* is in the position shown 10 in full lines, the springs 30 hold the contact strips yieldingly against the contacts 12, 13, and 14. As shown in Fig. 3, contacts 8 and 13 are connected together by a connector 13^a, at the rear side of the block *c*. Similarly the 15 contacts 12 and 6 are connected by a connector 12^a and the contacts 14 and 10 are connected by a connector 14^a. Thus, through the parts just described the contacts 6, 8 and 10 are normally connected to the supply wire 20 terminals, and when the magnet is energized the contactor 3, 4, and 5 will connect the contacts 6, 8, and 10 with the contacts 7, 9, and 11, respectively.

The contact 7 is electrically connected to 25 the hinged side bar 15 by a metal strip 31, and contact 11 is connected to the side bar 16 by a metal strip 32. The side bars thus serve as conductors for connecting the contacts 7 and 11 with the metal posts 17 and 18. 30 The contact 9 is connected by a wire 33 to a binding post 34. The leads 35, 36, and 37 to a multiphase motor *m* are shown connected to the post 34 and the posts 17 and 18, respectively. The coil of the magnet *b* is in a circuit which extends from the contact 6 through conductor 38 to a manually operated switch 39, thence by conductor 40 to the coil and by conductor 41 to the contact 8. Ordinary 35 stop and start push buttons will be employed 40 for controlling the magnet and when the main switch closes it will establish a holding circuit for the magnet, in accordance with the common practice, but for the sake of simplicity, I have shown a simple on and 45 off switch 39 for the magnet circuit.

The side bars 15 and 16 are shown in the form of channels and within the channels, at the free ends of the bars, are arranged links 50 42, of insulating material, which are pivoted to the bars and also to the end portions of a rod 43 which extends through arms 44^a of a bail 44. A rod 45 extends through the ends of the bail 44 and also through the arms 46^a of a bail 46 which is secured to the base *a*, 55 with its arms projecting upwardly therefrom. A sleeve 47 is journaled on one end of the rod 45 and carries a handle 48 which projects at right angles to the sleeve. A segment 49 is secured to the sleeve and the rod 43 projects through a segmental slot 50 in the segment as shown in Fig. 2. The links 42 and the arms 44^a form a toggle, the members of which normally stand in the position shown in Fig. 2. The springs *s* constantly tend to pull the side 60 rails and the block *c* toward the base. If

the operator moves the handle 48 downwardly, in Fig. 2, a certain distance, the toggle breaks and the springs *s* then quickly draw the side rails of the block from the full line position in Fig. 3 to the dotted line position, 70 thus moving the contacts on the block away from the contactor arms 3, 4, and 5 and from the contact strips 27, 28, and 29. By moving the handle 48 in the reverse direction, the side arms and the block will be raised and locked 75 in their upper positions.

The operation is as follows: Normally the block carrying the contacts is in the raised position. The operator starts the motor by closing the circuit to the magnet and he stops the motor by opening this circuit. When the magnet is energized its armature moves the switch arms or contactors 3, 4, and 5 into engagement with the pairs of main switch contacts 6—7, 8—9, and 10—11, and the motor 80 circuits are thus completed from the supply wires 51, 52, and 53 to the motor. When the operator wishes to stop the motor, he interrupts the circuit to the magnet and the arms 3, 4, and 5 fall into open position by gravity, 85 each arm making a double break in the leg of the motor circuit which it controls. 90

If, for any reason, such as grounding of the magnet coil, the main switch fails to open when the manually controlled switch 39 is 95 opened, the operator can quickly break the motor circuits by moving the handle 48 downwardly into position to unlock the toggle lever when the insulating block *c* will be quickly drawn to the dotted line position, thus 100 moving the main switch contacts on the block away from the arms 3, 4, and 5 and the line contacts 12, 13, and 14 away from the spring pressed connectors 27, 28, and 29. Each leg of the motor circuits will thus be broken so 105 that very little arcing will result. At the same time the circuit for the magnet will be broken at the contacts 6 and 9.

Blow-out magnets may be mounted on the contact-carrying block. In Figs. 6 to 8 of the drawings, I have shown, for illustration, a blow-out magnet mounted upon the movable contact-carrying block of a single-pole switch. In these figures, the main switch arm 55, which is controlled by the magnet *b*, is shown in closed position in engagement with a single contact 56 on an insulating block *c*¹ carried by pivoted brass arms 15^a and 16^a, and a spring-pressed contact member 57, extending from a line terminal 58, bears upon a 110 line contact 59 on the block. The base of the block is arched forwardly between contacts 56 and 59, as shown at 60, to accommodate the coil 61 of a blow-out magnet the core 62 of which extends transversely of the block 115 and is connected at its ends to sheet metal pole pieces 63 which lie in recesses 64 in the outer sides of the longitudinal arc-shields. Each pole piece is of the form shown in Fig. 9, having downwardly converging side edges 120

63^a and an opening 63^b near its lower end, and the recesses 64 which receive the pole pieces have their side walls converging downwardly as shown at 64^a, so that when the pole pieces are placed in the recesses they will be supported by the converging walls of the latter. The magnet core has pintles 62^a at its ends which extend into the opening 63^b in the pole pieces, and thus the core and its coil 10 are supported by the pole pieces. The pole pieces are held in the recesses by the brass side bars 15^a and 16^a. The terminals of the coil 61 are connected to the contacts 56 and 59 as shown in Fig. 7.

15 A toggle mechanism normally supports the block *c*¹ and side bars in the position shown in Fig. 7. This toggle, which operates the same as the toggle in the previously described figures, comprises a rod 65 journaled in a 20 bracket 66, which is secured to the base, a sleeve 47 secured to the shaft and a hand lever 48 projecting from the sleeve, which carries a slotted segment 49, the same as the segment in the previously described figures. 25 Links 67 connect the shaft 65 with a shaft 68, one end of which extends through the slot in the segment. A link 69, of insulating material, is pivotally connected to the shaft 68 and to the central part of a rivet pin 70 which 30 extends through the side bars 15^a and 16^a and the block *c*¹.

A supply wire 71 is shown connected to the binding post 58 and the other supply wire 72 is shown connected by conductor 73 to one 35 terminal of a motor *m*¹, and the other terminal of the motor is connected by wire 74 to a binding post 75. A flexible conductor 76 connects this binding post with the switch arm 55. The magnet circuit extends from 40 the switch contact 56 through conductor 77 to the magnet coil, and thence through manually controlled switch 65 to the conductor 73, and thence to supply wire 72.

In operation, the contact-carrying block is 45 normally held in the position shown in Fig. 7 and the supply wire 71 is normally connected to the contact 59 through spring-pressed connector 57. When the switch 65 is closed, the magnet attracts the armature 1 and the switch arm 55 is drawn into engagement with the contact 56. Current then flows 50 to the motor from supply wire 71 through binding post 58 and connector 57 to contact 59, thence through the coil 61 of the blow-out 55 magnet to contact 56, thence through switch arm 55, flexible conductor 76 and conductor 74 through the motor and thence through conductor 73 to the supply wire 72. When the switch 65 is opened, the magnet becomes 60 deenergized and the armature rocks by gravity away from the pole piece, carrying the switch arm 55 out of engagement with the contact 56, thereby opening the motor circuit and stopping the motor. The arc between the arm 55 and contact 56 is extin- 65

guished by the blow-out magnet. If this main switch fails to open by reason of grounding of the magnet coil, or for any other reason, the operator can break the circuit through the motor by swinging the hand lever 48 downwardly, thereby breaking the toggle, and the springs *s* will then swing the side bars and contact-carrying block toward the base, thus moving the main switch contact 56 away from the switch arm and the line contact 59 away from the connector 57 so that the motor circuit will be broken in two places, and the blow-out magnet will extinguish the arcs at both places. Also, the circuit through the magnet will be broken at these two places. 70 75 80

What I claim is:

1. A motor control switch mechanism comprising a normally stationary contact, a switch member having a limited range of movement toward and from said contact and biased away from the contact, a magnet for moving said member into engagement with the contact, and manually controlled means for quickly moving the contact beyond the range of movement of said member. 85 90 95

2. A motor control switch mechanism comprising a block of insulating material, a switch contact on said block, a switch member having a limited range of movement toward and from said contact and biased away from the contact, a magnet for moving said member into engagement with the contact, and manually controlled means for quickly moving the block to carry the contact beyond the range of movement of said member. 100 105 110

3. A motor control switch mechanism comprising a switch member having a limited range of movement, a block of insulating material, a switch contact on said block and normally within said range of movement, a magnet for moving said member into engagement with said switch contact, a line contact on the block, a stationary line terminal, a contact member extending from said terminal and normally engaging said line contact, and manually operable means for moving said block to carry said switch and line contacts out of engagement with said switch member and said contact member, respectively. 115 120 125

4. A motor control switch mechanism comprising a switch member having a limited range of movement, a block of insulating material, a switch contact on said block and normally within said range of movement, a magnet for moving said member into engagement with said switch contact, a line contact on the block, a stationary line terminal, a contact member extending from said terminal and normally engaging said line contact, said magnet having its coil connected to said line contact, and manually operable means for moving said block to carry said switch and line contacts out of engagement with said switch member and said contact member, respectively. 130

5. A motor control switch mechanism comprising a block of insulating material, a pair of switch contacts and a line contact on said block, one of said switch contacts being connected to said line contact, a switch member having a limited range of movement and adapted to engage and bridge said switch contacts, a magnet for moving said switch member into engagement with the latter contacts, a stationary line terminal, a contact member extending from said terminal and normally engaging said line contact, and manually operable means for moving said block to carry said switch and line contacts out of engagement with said switch member and said contact member, respectively.
10. A motor control switch mechanism comprising a block of insulating material, a pair of switch contacts and a line contact on said block, one of said switch contacts being connected to said line contact, a switch member having a limited range of movement and adapted to engage and bridge said switch contacts, a magnet for moving said members into engagement with the latter contacts, a stationary line terminal, a contact member extending from said terminal and normally engaging said line contact, said magnet having its coil electrically connected to said line contact, and manually operable means for moving said block to carry said switch and line contacts out of engagement with said switch member and said contact member, respectively.
15. 7. A motor control switch mechanism comprising a switch member having a limited range of movement, a movable block of insulating material, a switch contact on the block, a magnet for moving said member into engagement with said contact, a toggle mechanism adapted to hold the block and contact in position so that said member may engage the contact, and a spring adapted to move the block and contact away from said position when the toggle is tripped.
20. 8. A motor control mechanism comprising a switch member having a limited range of movement, a pair of levers, a block of insulating material mounted on said levers, a switch contact on the block, a magnet for moving said member into engagement with said contact, a manually operable toggle normally supporting the levers and block with the contact in position to be engaged by said member, and a spring adapted to move the levers and block to carry the contact out of the range of movement of said member, when the toggle is tripped.
25. 9. A motor control switch mechanism comprising a switch member having a limited range of movement, a block of insulating material, a switch contact on said block and normally within said range of movement, a magnet for moving said member into engagement with said switch contact, a line con-

tact on the block, a stationary line terminal, a contact member extending from said terminal and normally engaging said line contact, a blow-out magnet carried by the block and having its coil terminals connected to said contacts, and manually operable means for moving said block to carry said switch and line contacts out of engagement with said switch member and said contact member, respectively.

10. A motor control switch mechanism comprising a switch member having a limited range of movement, a block of insulating material, a switch contact on said block and normally within said range of movement, a magnet for moving said member into engagement with said switch contact, a line contact on the block, a stationary line terminal, a contact member extending from said terminal and normally engaging said line contact, a blow-out magnet carried by the block and having its coil terminals connected to said contacts, and its pole pieces adjacent both of said contacts, and manually operable means for moving said block to carry said switch and line contacts out of engagement with said switch member and said contact member, respectively.

In testimony whereof I affix my signature.

GEORGE H. WHITTINGHAM.
